Primary Examiner — Cathron C Brooks*Assistant Examiner* — W. A. Teddy Falloway(74) *Attorney, Agent, or Firm* — Lewis Brisbois Bisgaard & Smith LLP; Nigamnarayan Acharya(57) **CLAIM**

The ornamental design for a levitated polyhedron, as shown and described.

DESCRIPTION

FIG. 1 is a front perspective of a levitated polyhedron; FIG. 2 is a rear perspective view thereof; FIG. 3 is a bottom perspective view thereof; FIG. 4 is a top view thereof; FIG. 5 is a bottom view thereof; FIG. 6 is a left side view thereof; FIG. 7 is a right side view thereof; and, FIG. 8 is a side view thereof, showing the polyhedron rotated 45 degrees. The broken lines illustrate portions of the levitated polyhedron that form no part of the claimed design.

1 Claim, 8 Drawing Sheets(56)
